UNITED STATES PATENT OFFICE.

GEORGE A. MOWER, OF LONDON, ENGLAND, ASSIGNOR TO JUDSON L. THOMSON MANUFACTURING CO., OF WALTHAM, MASSACHUSETTS, A CORPORATION OF MASSACHUSETTS.

METHOD OF AND MEANS FOR SEALING RECEPTACLES.

Application filed May 28, 1927, Serial No. 195,119, and in Great Britain June 8, 1926.

This invention relates to the securing of protecting bands particularly in crates, packing cases and other like receptacles. Packing cases and the like containing contents of value are protected by means of metal bands secured around them, the object of these bands being to prevent the removal of any parts of the case or crate so that the contents cannot be made accessible without leaving the evidence that the case has been tampered with.

It has been found, however, that even with the ends of the bands sealed, it is possible, by carefully removing the nails to remove parts of the crate or case without actually removing or breaking the band and the parts can be replaced without leaving any trace that the case has been tampered with.

20 The object of the present invention is to provide a method of and means for securing the bands to the cases so that the securing nails or rivets cannot be removed without so damaging the case or crate and the securing band as to ensure detection.

The present invention comprises a method of sealing packing cases or receptacles by bifurcated rivets and bands or strips of metal extending over the cover and sides of the receptacles, consisting in punching from the strip at suitable intervals discs of metal and at the same time forcing such discs of metal into the material of the receptacle, a sufficient depth to form a spreading device over the edges of which the furcations of the rivet will spread outwardly into the material of the receptacle when driven therein through the punched hole in the band or strip of metal.

40 The invention consists in the combination and arrangement of parts set forth in the following specification and particularly pointed out in the claims thereof.

Referring to the drawings:—

45 Figure 1 is a plan view of a portion of a sealed packing case or receptacle embodying my invention.

Fig. 2 is a sectional elevation taken on the line 2—2, Figure 1.

50 Fig. 3 is a side elevation of a tool used in carrying my improved method into practical operation.

Like numerals refer to like parts throughout the several views of the drawings.

In the drawings, 2 is a punch having a 55 stop or shoulder 8 above the reduced portion 4 which is of such a diameter as to form a hole in a band or metal sealing strip 5, such hole being of such a size as to allow the driving through it of a bifurcated rivet 6. 60

The punching operation when the band or strip of metal 5 is in position on the packing case removes a small punching or disc of metal 3 and carries the same into the wood 7 a distance determined by the position of the shoulder 8 on the punch and so forms what may be termed an anvil for spreading in opposite directions into the wood the furcations of the bifurcated rivet 6 when the rivet 6 is driven through the 70 hole in the metal strip 5 into the wood 7. The two furcations of the rivet 6 are thus driven in and spread out in opposite directions in the wood 7 to such an extent that the rivet cannot be withdrawn without damaging the packing case. 75

It will, of course, be clear that the invention is applicable to any case where it is desired to secure a strip of metal to a wooden base in such a manner as to ensure detection if the removal of the securing nails or rivets is attempted. 80

I claim:—

1. A method of sealing packing cases or receptacles by bifurcated rivets and bands 85 or strips of metal extending over the cover and sides of the receptacle, consisting in punching from the strip at suitable intervals discs of metal and at the same time forcing such discs of metal into the material of the receptacle a sufficient depth to form a spreading device over the edges of which the furcations of the rivet will spread outwardly into the material of the receptacle when driven therein through the punched 90 hole in the band or strip of metal. 95

2. A receptacle, a metal band extending over the top and sides of said receptacle, and means for sealing the receptacle comprising a metal spreader rigidly embedded 100 in the material of the receptacle in alignment with a hole provided in said metal band and extending partly through said material, and a bifurcated rivet projecting through said hole with its legs spread on 105 opposite sides of said spreader, the diameter of said spreader being approximately the same as the shank portion of the rivet.

3. A receptacle, a metal band extending over the top and sides of said receptacle, and means for sealing the receptacle comprising a sheet metal disc rigidly embedded in the material of the receptacle in alignment with a hole provided in said metal band and extending partly through said material, and a bifurcated rivet projecting

through said hole with its legs spread on opposite sides of said spreader, the diameter of said spreader being approximately the same as the shank portion of the rivet. 10

In testimony whereof I have hereunto set my hand.

GEORGE A. MOWER.
